[57] **CLAIM**

The ornamental design for a paper set feeder, as shown and described.

DESCRIPTION

FIG. 1 is a view as seen from the front and upper left of a paper set feeder showing our new design;

FIG. 2 is a front end elevational view of the paper set feeder of FIG. 1;

FIG. 3 is a rear end elevational view of the paper set feeder of FIG. 1;

- FIG. 4 is a right side elevational view of the paper set feeder of FIG. 1;
- FIG. 5 is a left side elevational view of the paper set feeder of FIG. 1;
- FIG. 6 is a view as seen from the upper right of the paper set feeder of FIG. 1;
- FIG. 7 is a view as seen from the upper left of the paper set feeder of FIG. 1;
- FIG. 8 is a view as seen from the front and upper left of a second embodiment of a paper set feeder;
- FIG. 9 is a front end elevational view of the paper set feeder of FIG. 8;
- FIG. 10 is a rear end elevational view of the paper set feeder of FIG. 8;
- FIG. 11 is a right side elevational view of the paper set feeder of FIG. 8;
- FIG. 12 is a left side elevational view of the paper set feeder of FIG. 8;
- FIG. 13 is a view as seen from the upper right of the paper set feeder of FIG. 8;
- FIG. 14 is a view as seen from the upper left of the paper set feeder of FIG. 8;
- FIG. 15 is a view as seen from the front and upper left of a third embodiment of a paper set feeder;
- FIG. 16 is a front end elevational view of the paper set feeder of FIG. 15;
- FIG. 17 is a rear end elevational view of the paper set feeder of FIG. 15;
- FIG. 18 is a right side elevational view of the paper set feeder of FIG. 15;
- FIG. 19 is a left side elevational view of the paper set feeder of FIG. 15;
- FIG. 20 is a view as seen from the upper right of the paper set feeder of FIG. 15;
- FIG. 21 is a view as seen from the upper left of the paper set feeder of FIG. 15;
- FIG. 22 is a view as seen from the front and upper left of a fourth embodiment of a paper set feeder;
- FIG. 23 is a front end elevational view of the paper set feeder of FIG. 22;
- FIG. 24 is a rear end elevational view of the paper set feeder of FIG. 22;
- FIG. 25 is a right side elevational view of the paper set feeder of FIG. 22;
- FIG. 26 is a left side elevational view of the paper set feeder of FIG. 22;
- FIG. 27 is a view as seen from the upper right of the paper set feeder of FIG. 22; and,
- FIG. 28 is a view as seen from the upper left of the paper set feeder of FIG. 22.
